CLAIM

The ornamental design for a combined stress and pulse analyzer and chance promotion card dispenser, as shown.

DESCRIPTION

FIG. 1 is a perspective view of a combined stress and pulse analyzer and chance promotion card dispenser showing our new design.

FIG. 2 is a front view thereof;

FIG. 3 is a right side view thereof;

FIG. 4 is a left side view thereof;

FIG. 5 is a rear view thereof;

FIG. 6 is a top plan view thereof;

FIG. 7 is an exploded, fragmentary view of the display panel of the combined stress and pulse analyzer and chance promotion card dispenser.

FIG. 1
